INVENTOR
ALLAN G. MATHER

BY *Fetherstonhaughensis.*

UNITED STATES PATENT OFFICE.

ALLAN GILMOUR MATHER, OF OTTAWA, ONTARIO, CANADA, ASSIGNOR OF ONE-HALF
TO ALBERT EDWARD BRADBURY, OF OTTAWA, ONTARIO, CANADA.

OIL BURNER.

Application filed March 7, 1922. Serial No. 541,710.

To all whom it may concern:

Be it known that I, ALLAN GILMOUR MATHER, a subject of the King of Great Britain, and a resident of the city of Ottawa, 5 in the Province of Ontario and Dominion of Canada, have invented certain new and useful Improvements in Oil Burners, of which the following is a specification.

This invention relates to improvements in 10 oil burners, and the objects of the invention are to provide economically constructed and efficient means for utilizing liquid fuel in any form.

A further object is to provide means of 15 this character of the simplest construction and absolutely safe to operate.

A still further object is the substitution for coal and other solid fuel of an oil burner for boilers, furnaces, and the like to generate 20 heat more quickly without waste ashes, dirt or smoke, that is readily controlled to give perfect combustion to the limit of the air supply.

While the foregoing are only a very few 25 of the many objects aimed at in the heating of buildings and generation of heat generally, it may also be mentioned that the results obtained with my oil burner are achieved at an expenditure less than the cost 30 of coal or other solid forms of fuel.

With the foregoing and other objects in view, the invention consists essentially of the combination with controlled air blast and controlled oil supply means of a burner comprising a hollow member formed with an orifice in the bottom for a pilot light and designed at the top to receive therein a suitably apertured and interchangeable covering plate or top.

Referring to the drawings in which like characters of reference indicate corresponding parts in each figure and in which:

Figure 1 is a side elevation partly in section showing my invention fitted to a furnace.

Figure 2 is a top plan view of Figure 1.

Figure 3 is a plan view of the modified form of burner, showing divided air conduits.

Figure 4 is a sectional view of Figure 3.

Figure 5 is an enlarged sectional view of the diaphragm.

In the drawings:

In which A represents a furnace partly cut 55 away, of any standard make used for heat-

ing buildings and comprising grate bars B and a fire box C.

10 is a pan designed to rest on the grate bars B to catch any oil that may drip from the burner so that on the burner being ignited such drip will also be burned and the fire box maintained in clean condition, and 11 is the oil burner set on said pan at 12 and comprising a hollow, circular shaped member 13 provided with an inwardly slanting 65 or concave rim 14 designed to engage with the covering plate or top 15 having an aperture 16 therein. 17 is an opening in the side of the member 13 communicating with an air conduit 32 hereinafter more fully described. 18 is a pilot light of suitable construction arranged in the burner 11 connected by a gas conduit 19 extending there-through and outside the furnace to the source of supply and provided with suitable 70 valve means 20. 21 is the oil conduit designed at one end to extend through the side of the burner 11 adjacent to the air conduit 17 and formed with a reduced bore or discharge head 22 designed to discharge the oil 80 or liquid into the burner 11. Adjacent to the contracted discharge opening 22 and at 22^a in the oil supply conduit 21 is a dia-phragm 22^b which has a perforation smaller than the bore in the discharge nozzle 22. 85 This construction is an essential and most important feature of my invention and assures an even flow of oil or liquid without causing an uneven flame in the burner. The other end of this conduit 21 is connected to 90 a pressure pump 23 of any well known type and designed as here shown to be operated by a motor 24 through shaft 24^a suitably mounted adjacent to the furnace B and connects to the source of power by wires 25 95 having a switch control 26 and in turn connected to a thermostat 27. The flow of oil from the supply tank to the pump 23 and thence to the burner 11 through the conduit 21 is controlled by means of the oil control 100 valve 28, a uniform level of oil being automatically maintained in a reservoir 29 connected to the supply tank and the pump respectively and having therein a strainer 30 and a float operated valve 31. 32, as pre- 105 viously referred to, is the air blast conduit connected tangentially at one end with the burner 11 and having at the other end a fan 33 operated by the motor 24. Substantially intermediate of its length, between the 110

burner and said fan, the conduit 32 is provided with an air blast regulator 34 comprising an automatic shutter 35 controlled through a spindle 36 having a screw adjustment for air regulation thereon 37.

From the foregoing details of construction the operation of my device will be almost self evident. The approximate amount of heat required having been determined upon, 10 a plate apertured accordingly is dropped into the burner 11. The controls 28 and 34 in the oil and air conduits respectively are then set, pilot light 18 lit and the power turned on through the switch 26 when the 15 motor 24 starts operating the pump and fan to force the oil and air through the conduits 21 and 32 into the burner 11, the former through the pilot light 18 being immediately ignited and circulating in flames around the 20 inside of the burner 11 and out through the orifice 16 to constitute in the central flame through the orifice 16 one complete and perfect flame controlled as previously mentioned for all practical purposes by the 25 valve 28.

To put the burner out altogether, it is only necessary to open the switch when the burner ceases to operate leaving all the adjustments set ready to start when the switch is again 30 closed.

It will, accordingly be seen that the construction and operation of my device is not only thoroughly efficient, but is at the same time practically fool proof. There are no 35 complicated parts to get out of order and the plate 15 being one of an interchangeable series having various sized orifices therein, may be changed at once to suit requirements. Moreover, in view of its compact arrangement, the machine can be readily disconnected and removed from the furnace at any time without interfering in any way with the furnace in which it has been fitted. Similarly, while here shown as fitted to an ordinary 40 central heating house furnace, my device can with equally satisfactory results be fitted to any make of furnace, boiler or otherwise. The advantages obtained not only from an economical point of view, but also 45 from that of safety, absence of dirt and odors, can not be adequately appreciated outside of a practical working of the invention.

The device is here shown and dealt with in its application to domestic heating purposes, but it may also be used with the greatest advantage commercially on a much larger scale with, for instance, one fan to a number of burners with a separate motor for the pump etc. giving, however, in both cases 50 perfect combustion free from backfire and soot, the backfire and explosions being entirely eliminated through the construction of the oil supply conduit and automatic shutter in the air supply, the features of which 55 are the provision of a perforated diaphragm

in combination with a contracted discharge nozzle.

In my invention as illustrated in Figures 3 and 4, it will be noted that the air current is divided or split within the burner tangentially in opposite directions by means of a diaphragm centrally arranged in the air conduit, thereby tending to considerably decrease noise when the device is in operation. 70

As many changes could be made in the above construction and many widely different embodiments of my invention within the scope of the claims, constructed without departing from the spirit or scope thereof, it is intended that all matter contained in the 80 accompanying specification and drawings shall be interpreted as illustrative and not in a limiting sense. 75

What I claim as my invention is:

1. An oil burner comprising an annular 85 liquid fuel burning combustion chamber adapted to be readily inserted into and withdrawn from a fire-box, said chamber being designed to receive an interchangeable top or cover plate having an opening therein, 90 openings in the circular wall of said chamber communication with air blast oil-supplying means.

2. In combination, a heating device including a fire-box, a liquid fuel burning combustion chamber mounted in said fire-box and independent thereof, an interchangeable top or cover for the chamber having an opening therein, said chamber being formed with bulged circular side walls and having a concaved top rim adapted to receive said cover, 95 openings in the said walls communicating with air and liquid fuel supply means for the chamber, whereby, in combination with the bulged side walls and rimmed top, a 100 strata of oil-charged air is formed in the chamber preparatory to complete combustion. 105

3. An oil burner of the character described comprising a furnace grate, a burner designed to fit thereon in a suitable tray, an interchangeable cover plate for the burner, an aperture in said cover plate, oil supply means for the burner comprising a reservoir connected with the source of supply 110 and provided with a screen and a float controlled valve, a pump communicating with said reservoir, valve control, an oil conduit communicating with the pump and the burner, a diaphragm in the conduit having 115 a smaller opening than the hole in the delivery end whereby an even flow of oil is assured to the burner, an air blast for the burner and means communicating with the source of power for operating the air blast 120 and said pump, a pilot light in the burner and gas and air supply means therefor. 125

4. An oil burner of the class described comprising a furnace grate, a burner thereon having interchangeable and apertured 130

- covers or tops, an oil supply conduit having a perforated diaphragm therein and formed with a contracted discharge nozzle for said burner, blast means for the burner
- 5 comprising a conduit communicating at one end with the burner and provided with a fan at the other end, shutter control valve means for said conduit and means connected to the source of power for operating
- 10 said fan and supplying oil to the oil supply conduit.
5. In an oil burner as described in combination a furnace grate, a burner thereon having an interchangeable apertured top,
- 15 a pilot light in the burner, oil and air supply conduits communicating with the burner, control valves for regulating the supply of oil and air in said conduits, a perforated diaphragm in the oil conduit
- 20 designed in combination with the contracted nozzle on the conduit to provide an even flow of oil for the burner, a pump for the oil conduit, a fan for the air conduit, a motor designed to operate the pump and
- 25 the fan and means connected with the source of power for operating said motor, a reservoir connected to the oil supply source designed to supply said pump.
6. In a device of the character described
- 30 the combination with a burner having an interchangeable apertured top or cover of an oil supply conduit provided with a perforated diaphragm and a contracted nozzle and an air blast conduit with shutter control means, a pressure pump communicating
- 35 with the oil supply conduit, a fan for the air blast conduit and means connected to the source of power for operating the pump and said fan, a reservoir communicating
- 40 with the source of supply and with said pump and valve control means in the reservoir and for the pump.
7. In an oil burner for furnaces, boilers and the like, a burner provided with an
- 45 interchangeable and apertured top or cover, ignition means within the burner, a perforated diaphragm, conduit means having a contracted nozzle for delivering oil to said burner, an air blast conduit communicating
- 50 with the burner and provided with a control valve, pressure means for supplying
- oil and air to the conduits and means connected to the source of power for operating said pressure means, ignition means in said burner.
8. A crude oil burner of the character described comprising in combination a burner having an interchangeable apertured top or cover plate, an oil conduit, a perforated diaphragm therein, contracting
- 60 means at the point of discharge in said conduit, a split air conduit designed to communicate tangentially with said burner, means for supplying and regulating the oil and air under pressure through said conduits to the burner, means for operating
- 65 said supplying means and ignition means in the burner.
9. A crude oil burner of the character described comprising in combination a
- 70 burner having an interchangeable apertured top or cover plate, an oil conduit, a perforated diaphragm therein, contracting means at the point of discharge in said conduit, a divided air conduit designed to communicate tangentially with said burner, whereby noise is eliminated therefrom,
- 75 means for supplying and regulating the oil and air under pressure through said conduits to the burner, means for operating
- 80 said supplying means and ignition means in the burner.
10. A crude oil burner of the character described comprising in combination a
- 85 burner having an interchangeable apertured top or cover plate, an oil conduit, a perforated diaphragm therein, contracting means at the point of discharge in said conduit, air conduits designed to communicate tangentially with said burner, means for obviating the noise in the burner, means for
- 90 supplying and regulating the oil and air under pressure through said conduits to the burner, means for operating said supplying means and ignition means in the
- 95 burner.

In witness whereof I have hereunto set my hand in the presence of a witness.

ALLAN GILMOUR MATHER.

Witness:

H. T. CUFF LEWIS
